UNITED STATES PATENT OFFICE.

CHRISTOPHER TRICK, OF DAYTON, OHIO.

BONE-CUTTING MACHINE.

SPECIFICATION forming part of Letters Patent No. 744,647, dated November 17, 1903.

Application filed August 31, 1901. Serial No. 73,941. (No model.)

To all whom it may concern:

Be it known that I, CHRISTOPHER TRICK, a citizen of the United States, residing at Dayton, in the county of Montgomery and State of Ohio, have invented certain new and useful Improvements in Bone-Cutting Machines; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to bone-cutting machines whereby green bones and analogous articles are reduced for chicken and other animal food, and it more particularly relates to improvements in my Letters Patent No. 610,335, granted September 6, 1898, the improvements being in the construction of the grinding-cylinder and its shaft and in the feeding mechanism.

In the drawings illustrating my invention, 25 Figure 1 is a side elevation view of a machine embodying my improvements, the hand driving-wheel being removed. Fig. 2 is a plan view thereof, some of the parts being broken away on line X X of Fig. 1. Fig. 3 is a sectional elevation view on line X X of Fig. 2, and Fig. 4 is an enlarged view of the grinding-cylinder broken away to its longitudinal center.

In said drawings the parts similar to those 35 shown in my aforesaid Letters Patent are designated by the same numerals therein employed, while the improved parts are designated by letters.

The grinding-cylinder A has shafts B projecting from opposite ends and secured thereto by cross-arms C, rigid upon the inner ends of said shafts B and secured to the opposite ends of cylinder A by bolts D, threaded into the edges of cylinder A, thereby admitting 45 the hands or tools into the hollow of cylinder A for repairs, &c., as well as to facilitate the discharge of the ground food from the opposite ends of cylinder A that is admitted thereto through the openings in cylinder A 50 through which the knives 6 and 7 project.

The bore of said cylinder A is of a common diameter on both sides of the central dividing-wall E thereof and tapering outward therefrom and increasing toward the ends of cylinder A, at which ends the bore of said cylinder A is of the largest diameter, which also facilitates the discharge of the food.

Upon one of the shafts B and on one side only of the cylinder A is mounted an eccentric F, surrounded by a strap on one end of a pawl G, engaging ratchet-wheel H, secured to shaft I, provided with suitable bearings in a projection of the frame, wheel H being engaged by retaining-pawl J, also mounted upon said projection of the frame. Shaft I has secured thereto a gear-wheel K, adapted to be engaged by a rack or internally-toothed segment L, pivotally or otherwise secured to the end of arm 18 and adapted to be engaged by a flanged wheel or projection M, mounted 65 upon said projection of the frame. The teeth on rack L are so arranged that when the hopper 14 is empty the gear K will not engage more teeth on said rack L. (See Fig. 3.) The gear K is revolved by the reciprocation 75 of pawl G on wheel H, caused by eccentric F.

The member M is preferably a wheel to reduce friction, and in order to unmash and remesh rack L and gear K at different points said wheel M is adjustably mounted on the 80 frame, in the instance shown by being mounted on a member N, having shank n slidably mounted in a yoke O, removably secured to the frame by bolts o, and a spring P holds wheel M against rack L and maintains 85 the relative engaging positions of rack L and gear K.

Shafts B B have on opposite ends wheels R and S, respectively, for power and hand driving, wheel S having handle T for hand- 90 driving.

I claim—

The combination of a frame, a cutting-cylinder provided with trunnions and means for rotating the cylinder thereon, with an open 95 feed-hopper on the frame adjacent the cylinder, an arm pivoted on the feed-hopper and carrying a plunger to press the material fed to the hopper into contact with the cylinder, a bar provided with a plain part and a rack 100

connected with the free end of the arm, a shaft mounted on the frame, a pinion carried thereby engaging said rack, and with which the plain part of the bar comes in contact
5 when the plunger reaches the bottom of the hopper, a ratchet-wheel carried by the pinion-shaft, a pawl engaging said ratchet-wheel, and a second pawl engaging said ratchet-wheel, and means to reciprocate it

from one of the cylinder-trunnions and thereby rotate the ratchet-wheel and pinion.

In testimony whereof I affix my signature in the presence of two witnesses.

CHRIST. TRICK.
